UNITED STATES PATENT OFFICE.

ADAM McMEEKIN, OF DOAGH, IRELAND.

SWEAT-BAND.

SPECIFICATION forming part of Letters Patent No. 591,289, dated October 5, 1897.

Application filed February 13, 1897. Serial No. 623,302. (No model.)

To all whom it may concern:

Be it known that I, ADAM McMEEKIN, a subject of Her Majesty the Queen of Great Britain, residing at Cogry Mills, Doagh, in the county of Antrim, Ireland, have invented a certain new and useful Improvement in Sweat-Bands for Hats, Caps, and other Head-Coverings, of which the following is a specification.

10 My invention relates to an improvement in sweat-bands for hats, caps, and other head-coverings; and it consists in a new arrangement or combination of an air-tube with a sweat-band whereby an improved form of 15 yielding band is obtained which will enable the hat to fit easily on the head and present a slightly appearance in the interior.

In the accompanying drawings, which illustrate some forms of my invention, Figure 1 20 is a sectional end view of a sweat-band constructed according to my invention. Fig. 2 is a front view of same on a smaller scale. Fig. 3 is a back view of same.

According to my invention I combine with 25 the band 3 an elastic air-tube 1, or it may be more than a single tube, which is inclosed in a bag or casing 2, of woven fabric or of thin leather, secured to the lower margin of the sweat-band 3, so that the tube and bag are 30 supported at the back of the band. Such tube 1 may be of round, oblong, or other suitable section.

To form what is known as "brachering" or a border or finish to a sweat-band, it is frequently customary to employ a thin fiber of

cane, which is covered with a piece of fabric, or it may be leather and stitched to the inside of the hat or band. I combine this brachering with the band in the present case by inclosing the fiber of cane 4 in the fabric of the 40 bag or casing 2, such fabric being folded round same and secured by a line of stitching 5. The bag 2 is secured by a line of stitching 7, and the bag, including the fiber 2 and air-tube 1, is secured to the band by the line of 45 stitching 6, which stitching may be employed for securing the band in the hat, or a separate stitching may be employed for this purpose.

To produce a neat appearance inside the hat, I prefer to stamp or shape the bands 3 50 so that a swelled portion 8 is formed thereon, in the inside of which the bag 2 seats itself.

What I claim is—

In a sweat-band, the combination with the band, of a thin strip of flexible material having 55 its edges folded upon itself longitudinally and secured by a line of stitches, forming a larger and a smaller fold in said strip; an inflatable tube inclosed in the larger of said folds; a strip of fiber inclosed within the 60 smaller of said folds; and a line of stitching securing said folded strip to the edge of said band, substantially as described.

In testimony whereof I have hereunto set my hand in the presence of two subscribing 65 witnesses.

ADAM McMEEKIN.

Witnesses:

GEORGE McMEEKIN,
JOHN STALKER.
